United States Patent Office

Des. 180,365
Patented May 28, 1957

180,365

CABINET DOOR CATCH

Don Heyer, El Monte, Calif., assignor to International Research Corp., Los Angeles, Calif., a corporation of California

Application August 9, 1954, Serial No. 31,778

Term of patent 14 years

(Cl. D10—7)

Fig. 1.

Fig. 2.

Fig. 3.

Fig. 6.

Fig. 4.

Fig. 7.

Fig. 5.

Fig. 1 is a perspective view as seen from the front end of a cabinet door catch showing my new design;

Fig. 2 is a perspective view as seen from the rear end of the catch shown in Fig. 1;

Fig. 3 is a top plan view thereof;

Fig. 4 is a side elevational view thereof;

Fig. 5 is a bottom plan view thereof;

Fig. 6 is a front elevational view thereof; and

Fig. 7 is a rear elevational view thereof.

The essential and characteristic features of the design reside in the full line portion.

I claim:

The ornamental design for a cabinet door catch, as shown and described.
